UNITED STATES PATENT OFFICE.

BURT C. BUFFUM, OF DENVER, COLORADO.

GRAIN-HULLER.

1,242,136.

Specification of Letters Patent.

Patented Oct. 9, 1917.

Application filed May 3, 1917. Serial No. 166,161.

To all whom it may concern:

Be it known that I, BURT C. BUFFUM, a citizen of the United States, residing at the city and county of Denver and State of Colorado, have invented certain new and useful Improvements in Grain-Hullers; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in grain hullers, but is more especially adapted for use in removing the hull of the grain known as "emmer." The ordinary rice huller when used for removing the hull of emmer will not do the work effectually, because the emmer grain is covered with several glumes or coats of chaff which make the hull so bulky that the revolving cylinder which carries the grain against the blade to 20 remove the hull of rice, becomes clogged and the grain becomes surrounded with surplus hull, so that the rubbing action is not positive enough to remove all of it from all of kernels. This is true even where the 25 spout allowing the grain to escape from the huller is so nearly closed that it retains the grain under pressure, as the particles of hull removed will not be forced through the screen of the huller, but are retained within 30 the attrition cylinder.

35 By applying a suction of air regulated by a valve or other means whereby a partial vacuum is produced below the huller cylinder, I cause the air within the said cylinder 40 to be drawn through the meshes of the screen and in this way obviate the congestion of hulls within the cylinder, so that all of the grain can be subjected to a proper attrition to effectually remove the hull. Furthermore, this process enables me to greatly 45 increase the capacity of the machine.

I apply my improvement to a rice huller of the ordinary construction, the improvement consisting of a box or funnel composed 50 of any suitable material as tin, iron or wood, to which is attached a pipe leading to an

ordinary fan which creates the necessary suction. I make provision for allowing a limited quantity of air to enter the cylinder or cylindrical casing of the huller. This 55 may be done by the employment of wedges placed between the two hinged members of the cylindrical casing before these members are clamped together. By the adjustment of these wedges the quantity of air admitted may be easily regulated. Furthermore, on one or more sides of the box or funnel which is arranged below the discharge opening for the hulls, I provide 60 openings which may be regulated by means of valves or cut off devices of any suitable character whereby the entrance of air is controlled and the suction regulated. This same construction may be used in connection with a battery of hullers consisting of 65 two or more, each of the hullers being connected directly with the partial vacuum producing apparatus, in which event the amount of air passing through the hullers may if desired, be regulated by one or more valves 70 as with a single machine.

Having briefly outlined my improvement, I will proceed to describe the same in detail, reference being made to the accompanying drawing in which is illustrated an 75 embodiment thereof. In this drawing:

Figure 1 is a perspective view of a huller equipped with my improvement.

Fig. 2 is a vertical longitudinal section taken through the construction shown in 80 Fig. 1. This section is taken on the line 2-2 Fig. 3.

Fig. 3 is a cross section of the machine taken on the line 3-3 Fig. 2.

Fig. 4 is a fragmentary view of the machine illustrating the wedges inserted between the two parts of the cylindrical casing for supplying air thereto, the parts being shown on a larger scale than in the other views. This view is obtained by looking in the direction of arrow 4 Fig. 3.

Fig. 5 is a fragmentary detail view of the same structure which is the same as the lefthand side of Fig. 3, but shown on a larger scale.

The same reference characters indicate the same parts in all the views.

Let the numeral 5 designate the cylindrical casing of an ordinary rice huller, the same having an opening 6 at the top of one extremity through which the material to be treated is fed through the medium of a suitable hopper 7. Within this casing is mounted a rotary member 8 which is fluted or grooved as shown at 9 and through the medium of which the grain fed into the 10 casing is brought into contact with a blade 10 for hull-removing purposes. The grooved or fluted portion of the rotary member which is toward the receiving end of the casing has the ribs and grooves diagonally 15 arranged or inclined whereby the grain as the hull is removed is carried toward the opposite end of the casing which is provided with an opening 12 from which leads a spout 13 through which the hulled grain 20 passes from the machine. The casing 5 is composed of two members 14 and 15 which are hinged at 16. These members are provided opposite the hinge with opposing flanges 17 and 18 which are engaged by 25 U-shaped clamps 19, the said clamps being hinged at their lower extremities as shown at 20, their upper extremities being perforated to receive set bolts or screws 21 which are threaded in the upper extremities 30 of the clamps, their lower ends engaging the upper flange 17. One of my improvements consists in spacing these flanges before the clamping screws 21 are tightened. This spacing may be done in any suitable manner. 35 As shown in the drawing, I have illustrated wedges 22 which are placed between the two flanges and adjusted to give the desired space or opening 23 between the flanges in order to permit the proper quantity of air, 40 to enter the casing during the huller operation, to facilitate to the maximum degree the removal of the hulls through a bottom screen 24 which is applied to the lower part of the casing and extends across a bottom opening 25. I have found that by introducing air through the instrumentality of the construction just described, the removal 45 of the hulls through the screen 24 may be greatly facilitated.

50 The lower part of the cylindrical casing is provided with supports 26 which are made fast to a suitable base 27 which forms the top of a suction box 28 having inclined sides 29 tapering to a relatively small opening 30 which communicates with a pipe 31 leading to a suction producing device as a centrifugal fan 32.

The top of the box as illustrated in the drawing is provided with two openings 33 60 adjacent which covers 34 are pivotally connected with the top of the box for controlling these openings. By virtue of this construction, provision is made for admitting additional air directly to the suction box

during the hulling operation. Furthermore, 65 the extremity of the suction pipe 31 just in the rear of the hull outlet 30, has an opening which is controlled by a pivoted cover 35 which may be adjusted to permit the desired entrance of air to the suction pipe, in order 70 to further facilitate the removal of the hulls through said pipe and to prevent the possible clogging of the latter during the hulling operation.

When the machine is in use, the emmer 75 or other grain as heretofore indicated, is introduced into the hopper 7, the rotary member 9 being actuated through the medium of suitable power which may be connected with a pulley 36 which as illus- 80 trated in the drawing is made fast to an extension of one of the journals of the rotary member, the opposite journal being also extended and equipped with a fly-wheel 37. During the rotary movement of the member 85 9, the emmer or other grain under treatment is brought into engagement with the blade 10 which protrudes into the cylindrical casing and is properly adjusted to coöperate with the rotary member in loosening and re- 90 moving the hulls from the grain. As these hulls are removed, they are carried downwardly through the screen 24, through the medium of the suction produced by the suction member 32, the work being greatly 95 facilitated by the introduction of air through the opening 23 between the casing members, supplemented by additional air introduced by way of the openings 33 in the top of the suction box as well as by opening the pivoted 100 cover 35 at the rear end of the suction pipe 31. During the operation, the grain from which the hulls have been removed, is carried forwardly through the medium of longitudinally disposed ribs or flights, and 105 discharged through the opening 12 near the top of the casing into the spout 13 which may be supplemented by an additional conduit (not shown) which may carry the grain to any desired receptacle.

Having thus described my invention, what I claim is:

1. A grain huller including a casing, means arranged therein for separating the hulls from the grain, a casing having a 115 screen covered discharge opening for the hulls, means independent of the feed opening of the huller for introducing air into the casing above the screen, and suction-producing means in communication with the 120 discharge opening for the hulls.

2. A grain huller including a casing having a hinged member, means for preventing the complete closure of said member whereby a limited quantity of air is admitted to 125 the chamber of the casing, means within the casing for removing the hulls from the grain, a screen-covered opening for the dis-

charge of the hulls from the casing, and suction-producing means in communication with said last named opening.

3. A huller including a casing, means within the casing for removing the hulls from the material under treatment, the casing having a hull-discharge opening at its bottom, a suction box connected with

said opening, suction-producing means, a conduit connecting said box with said last 10 named means mounted upon said conduit, and means for introducing air in measured volume to said conduit.

In testimony whereof I affix my signature.

BURT C. BUFFUM.
